STOCKING AND METHOD OF MAKING SAME

Filed June 27, 1928

Attorney

UNITED STATES PATENT OFFICE

JOHN E. QUINN, OF NEW YORK, N. Y.

STOCKING AND METHOD OF MAKING SAME

Application filed June 27, 1928. Serial No. 288,559.

My invention has for its object the provision in a full-fashioned stocking of special strengthening of the toe portion and certain portions of the ankle where excessive wear 5 has a tendency to produce injury. More particularly, my improvements include the method of knitting of the toe as a separate structure and of different yarn or silk than employed in the leg and foot portion of the 10 stocking and subsequently securing the toe portion to the end of the foot portion by means of a looper such as commonly employed in closing the toe in a seamless stocking.

15 By making the toe portion separately upon a different machine from that upon which the body and foot portions are knitted, the toe portion may be made of heavier or different characters of yarn, obviating the necessity for the use of reinforcing or splice threads. The toe portions may be made flat and then looped to the end of the foot portion and the compound structure thus formed folded upon itself and seamed as is customary 20 in full-fashioned hosiery. Also, it will be understood that, if desired, the toe portion may be made as a pocket such as formed in seamless hosiery, and this looped on to the full-fashioned toeless foot after the same has 25 been seamed along the bottom of the foot portion.

The other feature of my improvement comprises the knitting of the back portion of the ankle with a splice thread so that it is reinforced in the usual manner and causing that 30 part of the reinforced portion just above the heel to be knitted with tight stitches while retaining the splice thread. This provides a strong dense reinforced portion for the stocking where it chafes upon the upper rear edge 35 of the slipper or shoe.

40 My invention also includes the method of forming the completed stocking with a toe separately made and attached, as hereinafter 45 more fully described.

With the above and other objects in view, the nature of which will be more fully understood from the description hereinafter, the 50 invention consists in the novel construction of stocking and method of making same, as

hereinafter more fully described and defined in the claim.

Referring to the drawings: Fig. 1 is a side view of the ankle and foot portions of a stocking embodying my improvements; Fig. 2 is a 55 plan view of the end of the full-fashioned foot and the separately made full-fashioned toe portion before they are united and seamed; and Fig. 3 is a perspective view of a seamless toe pocket adapted to be looped 60 on to the forward end of the foot portion to provide a modified construction of my invention.

The ankle portion is shown at 2 and 3 is the 65 foot portion. The toe portion 4 is shaped as in a full-fashioned stocking, but made with the toe portion knit separately and united with the forward end of the foot portion by being interlooped therewith along the line 10, preferably before being seamed along the 70 bottom lines 14 and 15. As is well known, the full-fashioned stocking is knitted flat and then folded upon itself and the selvage edges united by a seaming machine. I have shown in Fig. 2, the toe fabric and foot end which 75 would ordinarily be knitted as a continuous fabric before being seamed and these parts will need no special description as to their specific knitting.

More specifically referring to Fig. 2, 3a 80 is the flat end portion of the foot and has the selvages 11, 11, to be subsequently united along 14 at the bottom, as in Fig. 1. The separately knitted toe portion 4a is knitted 85 in the flat and of the general shape shown, having the selvages 12, 12, to be united along 15 in Fig. 1, and selvages 18, 18, to be united along line 19 in Fig. 1. In this manner, a separate toe pocket is made and its edge 16 is then looped upon the edge 17 of the foot 90 portion 3a, as in Fig. 1 at 10. It is manifest that for perfect results, the number of 95 stitches or loops along the adjacent edges 16 and 17 of the toe and foot should be the same, irrespective of the fact that the toe pocket 4 may be of an entirely different character of yarn or thread than employed in the foot and leg portion of the stocking.

The fact that the toe pocket may be knitted 100 of cotton or other strong but relatively

cheap yarn, as compared with the silk employed in the rest of the stocking, provides the dual benefit of durability and saving in cost.

There is still another and most important benefit to be derived by my improvement, namely, the prevention of a runner extending beyond the toe into the foot and instep of the stocking. This result is due to the fact that the joinder of the interlooped edges 16 and 17 by the looper thread along the line 10 will definitely prevent any runner in the toe 4 extending beyond the interlooped joinder line 10. This line of looper joinder may be formed part way down in the toe as on dotted lines $x-x$, Fig. 1.

Heretofore, when the full-fashioned toe portions were integral extensions of the foot portion and of the same delicate silk threads, any breakage of the thread by creation of a hole instantly provided a potential runner which at the first opportunity would extend up the full length of the stocking, ruining it. The danger of providing a hole in the toe is ever present in use and any means, such as my improvement, which will prevent such holes extending into runners is most desirable.

Referring now to the toe pocket construction, when made on a seamless hosiery machine: Fig. 3 shows such a pocket which, if made upon a knitting head having the same number of needles as required to knit the foot portion 3 of the full-fashioned stocking, may be readily interlooped into connection with the foot portion by the looper thread, as at 10 in Fig. 1. In Fig. 3, the toe pocket is shown at 4b, the gussets or narrowings are shown at 4c, and the end to be looped is shown at 16a. In attaching this seamless toe pocket, it is desirable that it first be split along its length, as at 12a, and inverted, so that its end 16a may be opened flat for being placed upon the needles of the looper bar together with the knitted sole end 17 and united by the looper thread or yarn. When the toe end has been attached to the sole portion as above described, the selvage edges 11, 11, of the sole are seamed together along the line 14 at the bottom of the foot portion and at the same time the edges adjacent to the slit portion 12a are re-united along the seam portion 15 which is in continuous alignment with the seam portion 14 of the sole. This will complete the foot portion of the stocking where a seamless toe pocket is employed in connection with a full fashioned leg and foot portion. I therefore do not restrict myself to any particular structure of the toe pocket, as the same may be completed before being interlooped upon the foot portion along the line 10 of Fig. 1 and after the foot portion has been seamed along the line 14, or wherein the toe pocket is completed after it has

been knitted in the flat and united along the lines 16 and 17 of Fig. 2, or split and attached along the line 16a as above indicated when referring to Fig. 3.

Referring now to the reinforced rear ankle portion above the heel, I have shown at 5, 6 and 8, areas reinforced with loose stitches and a knitted-in splice thread in the ordinary way; but in that portion indicated at 7, immediately at the rear of the ankle and just above the heel, I put the regular thread (and desirably the splice thread also) under greater tension, so that this portion 7 is more densely knitted and hence stronger than the portions 5, 6 and 8. The denser knitting of the portion 7 is more noticeable than the more loosely knitted portions 5, 6 and 8, and for that reason I confine this portion 7 to the limited areas where positive contact with the shoe or slipper rim creates friction, and this leaves the looser reinforced knitting 6 to a considerable distance above it and preferably on each side of it, as at 7; but the extents of this tight and loose reinforced knitting may be varied within the spirit of my invention.

I have described my improved method and the article of manufacture produced thereby, but I do not restrict or confine myself to the minor or secondary details either as to the method of procedure or the means employed in putting it into effect, as variations therein may be resorted to as matters for the skilled artisan and without a departure from the spirit of the invention.

Having thus described my invention, what I claim and desire to secure by Letters Patent is:

The herein described stocking comprising the leg, ankle and foot portions, combined with a separately formed toe pocket united to the foot portion by a transverse course of interlooping stitches, whereby the knitted structures in the foot portion and in the toe portion are independent but conjointly form part of a completed stocking, and wherein further, the foot portion and the toe portion are each made in flat knitted form of full-fashioned construction before said parts connected end to end by interlooping stitches, and in which also, the selvage edges of both the sole and toe portions are united along the foot portion in common alignment.

In testimony of which invention, I hereunto set my hand.

JOHN E. QUINN.
